UNITED STATES PATENT OFFICE.

JOHN DUNCAN, OF NEW HAVEN, CONNECTICUT.

ELECTRIC SWITCH.

1,257,198.

Specification of Letters Patent. Patented Feb. 19, 1918.

Application filed December 28, 1916. Serial No. 139,390.

To all whom it may concern:

Be it known that I, JOHN DUNCAN, of New Haven, in the county of New Haven and State of Connecticut, have invented certain new and useful Improvements in Electric Switches, of which the following is a specification.

This invention relates to switches for electric motors and has particular reference to devices of this character which automatically make and break the motor-operating circuit at such times as are required by the condition of the mechanism that is driven by the motor.

A particular object of my invention is to provide an improved switch for controlling the operation of an electric motor employed for winding a spring motor such as used in phonographs. I do not limit myself, however, to such application of the switch, and therefore I do not illustrate any spring motor but reserve the right to apply my improved switch and its automatic shifting mechanism to any mechanism which is driven by an electric motor, which driven mechanism carries rotating members to actuate the star-wheels of my improved switch-shifting mechanism.

Of the accompanying drawings:

Figure 1 is an elevation of my improved mechanism, looking from what would be the inner side in use, meaning, by "inner side" that side which would be next to the mechanism which operates the switch and which mechanism is not necessary to illustrate herein for reasons which will be presently understood.

Fig. 2 is a side elevation, partly broken out, the switch being closed.

Fig. 3 is a view from a direction opposite to that in Fig. 1.

Fig. 4 is a view similar to Fig. 2, showing the switch open.

Fig. 5 is an end elevation from the right of Fig. 2.

Figs. 6 and 7 are sectional views of the two star wheels and their sleeves and motion retarding disks.

Similar reference characters indicate similar parts in all of the views.

The frame 1 has bearings 2 for two rotatable hubs in alinement, a rod having a screw portion 3 and a squared portion 4 extending through said hubs. The two hubs are alike excepting as to their portions through which the rod 3, 4, passes. One hub

has a square aperture fitting the square portion 4 of the rod and has a notched disk 5 at one end and a star wheel 6 at the other end. The other hub has a threaded aperture (Fig. 60 7) fitting the screw 3 and has a notched disk 5' at one end and a star wheel 6' at the other end. The disks and star wheels of the hubs so engage opposite ends of the bearings 2 that they have no movement other than ro- 65 tary.

Mounted on a smooth cylindrical intermediate portion of the rod is a sleeve 7 having pins 8 projecting from opposite sides, a screw 9 tapped through one side of the sleeve 70 entering an annular groove (Fig. 2) in the rod whereby the rod, when shifting longitudinally, will carry the sleeve with it whether the rod is rotating or not during such shifting, so that said sleeve serves as an actuator 75 for the circuit breaker as hereinafter described. A pair of arms 11 having jaws extending past the pins prevent the sleeve 7 from rotating owing to the engagement of said jaws with the pins 8. The arms 11 are 80 connected by a pin 14 mounted in the upper ends of uprights 10 projecting from the inside of the frame 1, and the ends of the arms opposite their jaws are connected by a swivel bar 15, the purpose of which will presently 85 be explained. A stop plate 12 secured to one of the uprights 10 (Figs. 2 and 4) has two wings bent over the edges of said upright, said wings projecting below one of the arms 11. As both arms 11 are connected to oscillate together, their limits of movement between the positions shown by comparing Figs. 2 and 4 are prescribed by the wings of 90 stop plate 12.

A pair of arms 13, pivotally mounted on 95 the pin 14, are connected at their outer ends by a bridge plate 16 the ends of which are bent (Fig. 1) to make sliding contact with the flat bent ends of the stationary contacts 19 (Figs. 3 and 4). A longitudinally ex- 100 panding spring 18 confined between the bar 15 and a bar which connects the arms 13 operates to throw or snap the circuit breaker comprising the arms 13 and plate 16 whenever the rocking of the operating arms 11 105 from the Fig. 2 position to the Fig. 4 position, or vice versa, carries the bar 15 past the plane of the radius of arms 13. In the Fig. 2 position the upper wing of stop plate 12 arrests operating arms 11 while the contacts 19 arrest the circuit breaker, and in the Fig. 4 position the lower wing of stop plate 110

12 arrests the operating arms 11 while the circuit breaker is arrested by a stop 17 consisting of a wire in inverted U-form, the ends being secured to the sides of the frame (Fig. 2) and its mid-portion crossing from side to side as shown in Fig. 1.

The contacts 19 are carried by an insulating block 25 secured to the frame, and wires 20, 21, lead from said contacts to the motor 10 which is to be controlled.

To hold the star wheel 6' stationary when it is not positively actuated I provide a housing 22 for a plunger 23 which is held by a spring 24 (Fig. 5) in contact with the disk 15 5' which is preferably notched to enable the plunger to more firmly hold it and its hub and star wheel 6'. A similar device acts to hold or retard motion of the other star wheel 6.

20 The operation of my improved switch is effected by anything which will impart intermittent rotation to the star wheels. For instance, a well-known type of spring motor for operating phonographs and other mechanisms which should have constant speed, includes two springs one of which acts upon and through the other. A disk (which may be a part of a spring casing) or a gear carried by one of these springs revolves when 25 the motor is being wound up, and another disk or gear carried by the casing or shaft of the other spring revolves when the whole is imparting its power to the phonograph or other mechanism to be driven; in other 30 words, when the spring motor is "running down." To understand the operation of my present invention, it may be assumed that each of said two revolving disks or gears carries a series of pins or projections which 35 successively engage a star wheel and impart thereto a partial rotation. In the type of spring motors referred to, both of the said disks or gears always rotate in the same direction. Therefore rotation of either star 40 wheel will shift the rod 3, 4 lengthwise and carry with it the sleeve 7 the pins 8 of which, by engaging the jaws of arms 11, rock the latter until the circuit breaker 13, 16 snaps across as indicated by comparing Figs. 2 45 and 4 to open or close the circuit.

When this switch mechanism is in use with an electric motor geared to wind a spring motor of the character referred to, it is so connected that when the switch is in 50 the Fig. 2 position the electric motor is winding the spring motor, and the latter, by such pins or projections of one disk or gear as described, intermittently rotates one star wheel and causes the rod to move to the Fig. 55 4 position, at which time, the spring motor having been sufficiently wound, the circuit is broken and then the pins or projections of the other disk or gear will intermittently rotate the other star wheel until the rod shifts

65 back to the Fig. 2 position to cause the electric motor to run again. The movements of the rod as described is due to the fact that the hubs of the two star wheels can not move in the direction of their axes, and when only the star wheel 6 is being rotated, the rod is 70 rotated and is caused to move endwise by its threads coacting with the threads in the hub of star wheel 6' which acts as a stationary nut. When only the star wheel 6' is rotated, the hub of star wheel 6, by its engagement with the square portion of the rod, prevents the rod from rotating and therefore the threaded hub of the star wheel 6' acts to shift the rod endwise. My improved 75 automatic switch will, when utilized with or connected to, a spring motor having an electrical winder, as described, cause the rod to shift in one direction or the other and effect a completion or a breaking of the motor circuit, according to whether the spring motor 80 needs winding up or not. And this is effected without possibility of the spring motor being over-wound or running down too far, and without interfering with the usual hand winding of the spring motor if the current should fail.

Having now described my invention in one of its embodiments, without attempting to disclose all possible uses thereof, what I 85 claim is:

1. An electric switch comprising a circuit breaker, a longitudinally movable rod, a circuit-breaker-actuator mounted on the rod and movable with it, connections whereby movements of the rod in one direction or the other will shift the actuator and cause the circuit breaker to open or close a circuit, and means for intermittently operating said rod.

2. An electric switch comprising a circuit breaker, a longitudinally movable rod, connections whereby movements of the rod in one direction or the other will shift the circuit breaker to open or close a circuit, a pair of star wheels, one having a screw thread connection with the rod and the other being mounted to rotate with the rod while permitting the rod to slide through it, and means for preventing movement of the star wheels in the direction of their axes.

3. An electric switch comprising a circuit breaker, a longitudinally movable rod, connections whereby movements of the rod in one direction or the other will shift the circuit breaker to open or close a circuit, a pair of star wheels, one having a screw thread connection with the rod and the other being mounted to rotate with the rod while permitting the rod to slide through it, and means for preventing movement of the star wheels in the direction of their axes, means being provided for holding the star wheels stationary when not positively actuated.

4. A switch for automatically controlling

- an electric motor for winding a spring motor, said switch comprising a screw, a nut fitting the screw, a rotary member connected with the screw to rotate it while permitting the screw to shift endwise relatively to it, means whereby the nut or the rotary member may be rotated by the spring motor, and a circuit breaker connected with the screw and adapted to be shifted by endwise movements of the screw.
5. In a switch of the character described, a circuit breaker, contacts coöperating therewith, a rocking member for actuating the circuit breaker, a screw threaded member having connections for oscillating the rock-
- ing member, and means for rotating the screw threaded member and shifting it endwise.
6. In a switch of the character described, a circuit breaker, contacts coöperating therewith, a rocking member, yielding connections between the circuit breaker and rocking member, a screw threaded member having connections for oscillating the rocking member, and means for rotating the screw 20 threaded member and shifting it endwise.
- 25
- In testimony whereof I have affixed my signature.

JOHN DUNCAN.
